CLAIM

The ornamental design for interactive kiosk as shown and described.

DESCRIPTION

1. Interactive kiosk

1.1 : Perspective

1.2 : Front

1.3 : Back

1.4 : Left

1.5 : Top

1.6 : Bottom

1.7 : Reference view

1.8 : Perspective

1.9 : Front

1.10 : Back

1.11 : Left

1.12 : Top

1.13 : Bottom

1.14 : Reference view

The claimed design is an interactive kiosk that adjusts the height of the transparent display according to the user; the right side view is omitted because it is a mirror image of the left side view; reproduction 1.1 to 1.6 show the claimed design in a first position; reproduction 1.8 to 1.13 show the claimed design in which the transparent display has moved downward; reproductions 1.7 and 1.14 respectively show the state when adults and children use the claimed design and the broken lines in reproductions 1.7 and 1.14 form no part of the claimed design.

1 Claim, 14 Drawing Sheets
